UNITED STATES PATENT OFFICE.

WILLIAM E. EDWARDS, OF NEW YORK, N. Y.

DESIGN FOR A BADGE.

41,259.

Specification for Design.

Patented Mar. 28, 1911.

Application filed January 13, 1911. Serial No. 602,521. Term of patent 7 years.

To all whom it may concern:

Be it known that I, WILLIAM E. EDWARDS, a citizen of the United States, residing in the borough of Brooklyn, city of New York, in the county of Kings and State of New York, have invented a new, original, and ornamental Design for Badges, of which the following is a specification, reference being had to the accompanying drawing, forming part thereof.

The figure is a plan view of a badge, showing my design.

I claim:

The ornamental design for a badge, as shown.

WILLIAM E. EDWARDS.

Witnesses:

J. J. KOZINN,
W. WALLACE HURD.

Copies of this design may be obtained for five cents each, by addressing the "Commissioner of Patents, Washington, D. C."
